UNITED STATES PATENT OFFICE.

JACOB HEINRICH, OF NUERMBERG, GERMANY, ASSIGNOR TO THE FIRM OF METALLPAPIER- BRONZEFARBEN-BLATTMETALLWERKE AKTIENGESELLSCHAFT, OF MUNICH, GERMANY.

CONTROL DEVICE FOR SHEET-SEPARATORS.

1,092,359.

Specification of Letters Patent.

Patented Apr. 7, 1914.

Application filed September 18, 1913. Serial No. 790,425.

To all whom it may concern:

Be it known that I, JACOB HEINRICH, subject of Germany, residing at Nuremberg, Bavaria, Germany, have invented certain new and useful Improvements in Control Devices for Sheet-Separators; and I do hereby declare the following to be a full, clear, and exact description of the invention, such as will enable others skilled in the art to which it appertains to make and use the same.

The invention relates to the periodical connection of pneumatic conveyers with the appurtenant air pumps for machines for disassembling stacks of metal foil, wherein a plurality, for instance two or three positively controlled pneumatic conveyers or suction devices periodically served by a pump are employed, one of said conveyers lifting the separating layers off the pack to be disassembled with a rising movement, and the other conveyer with a lateral movement lifting off the sheets of metal foil. For this purpose there is arranged in the suction conduit between the pump actuating the suction device and the latter itself a distribution device which serves to suddenly throw the suction device into and out of operation.

Two embodiments of the invention are shown in the accompanying drawings, in which:—

Figure 1 is a schematic view, illustrative of the improved distribution device connected to a constantly operating pump, the latter appearing in section. Fig. 2 is a sectional side view, and Fig. 3 a plan view, while Fig. 4 is a section of a modified form of distribution device.

In both forms of construction the distribution device is provided with a cock or valve housing *k*, which is connected to the air pump *l* by an air delivery pipe *m*, and to the suction devices by one, two or more feed pipes *n o*, alternately fed by the pump and corresponding in number with the number of said suction devices with which the machine is provided for disassembling the stacks. This alternate connection to the common suction pipe is known.

The invention consists in those parts which effect the precise movement of the valves.

In order to alternately feed the pipes *n o* from the constantly operating pump *l*, two relatively displaced cams *q q¹* are mounted on a constantly rotating shaft *p*, and bearing on said cams at both sides are two pivoted levers *r r¹* and *s s¹*, each pair being connected by a spring *x*. These levers either operate two slide valves *t t¹* (Figs. 2 and 3) or two puppet valves *u u¹* (Fig. 4), one of said valves controlling the pipe *n* and the other the pipe *o*. The control of the slide valves *t t¹* and the valves *u u¹* is effected by the levers *r r¹*, *s s¹*, of each pair of levers by said levers being provided with abutments which may be in the form of pins *v* which act against shoulders on bars *w w¹*, which latter are pivoted to the slide valves *t t¹* (Figs. 2 and 3) and fixed to, or arranged to carry, the puppet valves *u u¹* (Fig. 4). The arrangement of both pairs of levers is preferably such that one lever drops off the cam surface after the other lever has risen onto the crest of the cam surface, the levers operating their valves when they leave the cam surface. This arrangement insures a sudden opening and closing of the valves and consequently a reliable action of the suction devices.

What I claim as my invention and desire to secure by Letters Patent of the United States is:—

1. An air distributing valve, embodying a casing having ports connected with suction devices, a constantly rotating shaft traversing said casing, a cam set on said shaft, a pair of pivotally mounted, flexibly interconnected levers within the casing and engaging the surface of said cam at opposite sides of said shaft, and valves within said casing actuated by said levers to control the supply of air to said ports.

2. An air distributing valve, embodying a casing having ports connected with suction devices, a constantly rotating shaft traversing said casing, a cam set on said shaft, a pair of levers pivoted within the

casing at opposite sides of the shaft, a spring connecting said levers and for normally holding the same in contact with said cam, valves for controlling the supply of air to the ports, bars connected to said valves, and means on said levers acting against said bars to operate said valves.

In testimony whereof I hereunto affix my signature in the presence of two witnesses.

JACOB HEINRICH.
